ARCHITECTURAL PANEL CONSTRUCTION

Filed Sept. 4, 1945

UNITED STATES PATENT OFFICE

2,416,240

ARCHITECTURAL PANEL CONSTRUCTION

Carl G. Strandlund, Oak Park, Ill., assignor to
 Chicago Vitreous Enamel Product Company, a
 corporation of Illinois

Application September 4, 1945, Serial No. 614,379

6 Claims. (Cl. 189—86)

1

The present invention relates generally to architectural porcelain enamel panels, but more particularly to a novel and improved construction and an arrangement of interlocking and sealing adjacent porcelain enamel panels, units or adjoining connecting parts of the exterior or interior walls of a building or structure of any type or design.

It has been the practice heretofore in the architectural porcelain enamel industry to provide special metal clips for attaching the porcelain enamel panels or units to the exterior or interior of a building and attempts have been made to seal the intervening or contiguous edges and corners of the panels or units with a waterproof caulking compound. This practice not only required trained experts to install the units, but also proved unsatisfactory because the caulking compound between the panels or units did not provide for the expansion or contraction of the steel panels or units due to changes in temperature with the result that the caulking compound cracked and separated from the adjoining panels, thus breaking the seal and leaving an unsatisfactory appearance to the whole wall structure.

It is, therefore, one of the primary objects of the present invention to not only overcome the disadvantages hereinbefore pointed out, but to also provide a novel construction or interlocking and interfitting panels or units and means for permanently sealing the same so that expansion or contraction will not break or disrupt the seal.

Another object of the invention is to provide a novel and improved panel or unit construction in which means are provided for insulating each panel or unit from the adjacent ones and sealing the adjoining marginal edges so as to form in effect an air tight insulated wall structure.

A further object of the invention is to provide a novel and improved interlocking porcelain enamel panel or unit and seal therefor which will not require the services of a skilled artisan to install.

A still further object of the invention is to provide interfitting core of plastic composition between the adjacent panels or units which will insure a permanent seal and which will not crack or separate from the adjoining panels or units regardless of variations in temperature.

These and other objects are accomplished by providing a construction and an arrangement of the various parts in the manner hereinafter described and particularly pointed out in the appended claims.

2

Referring to the drawings:

Fig. 1 is a perspective fragmentary and partly broken view showing the manner of interconnecting the panels or units together;

5 Fig. 2 is an enlarged front elevational view of one of the panels or units showing a portion of the adjacent panels or units;

Fig. 3 is an enlarged cross sectional view taken on the lines 3—3 in Fig. 2; and

Fig. 4 is an enlarged cross sectional view taken on the lines 4—4 in Fig. 3.

In illustrating one form my invention may assume in practice, I have shown the same as comprising a square panel or unit generally indicated 10 by the reference character 10. This panel can be made in a variety of shapes and forms and the invention of the interlocking and sealing means may be embodied in the interior or exterior structure of a building so that baseboards, ceilings, 15 window and door frames, copings and the like 20 may be interlocked, sealed and insulated.

The panel or unit 10 is preferably made of flat sheet steel of suitable gauge, with the four corners thereof suitably cut out as shown at 12 25 prior to forming or bending the interlocking flanges hereinafter described. The panel 10 has a relatively flat plane surface 11 with two of its adjacent lateral edges as shown at 13 and 14 bent at right angles to the plane surface 11. The 30 inturned edges 13 and 14 are formed or connected to the plane surface 11 of the panel by a quarter circular curve as shown at 15. The inner portions of each of the edges 13 and 14 terminate in outwardly projecting flanges 16 and 17. The flanges 16 and 17 occupy the same plane which 35 is positioned parallel to and inwardly of the plane 11 of the panel 10. The other adjacent lateral edges of the panel 10 are similarly bent at right angle as shown at 18 and 19 with quarter circular curves therebetween as shown at 20. The inner portions of each of the lateral edges 18 and 19 are bent at right angles as shown at 21 and 22 respectively. The portions 21 and 22 lie in the same plane which is located inwardly 40 of and parallel to the plane surface 11 of the panel. These portions 21 and 22 have their inner end curved or looped as shown at 23 and 24 respectively to form in effect channel-like recesses 25 with the outer ends as shown at 26 forming flanges projecting beyond the marginal edges 18 and 19 respectively of the panel. In 45 this connection it will be noted that the outwardly projecting channels or recesses 25 formed by the flanges 26 and walls 21 and 22 on the respective marginal edges 18 and 19 are so ar-

50

ranged or positioned that the flanges 16 and 17 of the adjacent panels occupy central positions therein and the units or panels are held out of contact with a special form of sealing core generally indicated by the reference character 21.

This sealing core 21 may be made of a rubber composition, but is preferably made of a plastic composition possessing the properties of flexibility so as to allow for contraction and expansion, of the steel panels or units. The core 10 also embodies the property of vulcanization so that the severed ends of the sealing core at all the corners of the panels may be vulcanized by the application of heat after the panels are installed for completely sealing the structure. This sealing core 21 is formed in relatively long strips, the cross section of which conforms with and is complementary to the channel-like recesses 25, flanges 16 and 17, as well as the space between the marginal edges of the adjacent panels or units as clearly shown in Figs. 3 and 4 of the drawings. The core is substantially L-shape in cross section and is provided with a slot or slit 28 for the reception of the flanges 16 and 17 of the panel or unit.

The sealing core is preferably cut into lengths as shown at 28 of substantially the length of the marginal edges of the panels and one of the ends of each length is cut on a bevel of 45° as shown at 29 so as to correspondingly fit and lie contiguously to the similarly bevelled end of the adjacent length of core. The other end of the core strip is cut off at right angles as shown at 30 so as to lie contiguously with the longitudinal side of the adjacent core strip as clearly shown in Figs. 1 and 2 of the drawings.

The flanges 17 and 26 of the panels are provided with suitable spaced apart apertures 31 so that suitable nails or screws may be used to fasten the panels to the superstructure or framework of the building.

After the sealing core strips 28 have been fitted onto the flanges 16 and 17 by inserting these flanges into the slot 28 of the plastic core 21, the core 21 with the panel flanges 16 and 17 are then inserted into the outwardly projecting recesses 25 of the lower and lateral adjacent panels in the manner shown in Fig. 2 of the drawings. Suitable nails are then placed in the one or more of the exposed flanges 26 of the last positioned panel to secure the same to the superstructure. After the panels are assembled in interlocked position with the sealing core interlocked between the adjacent panels, a heated vulcanizing iron is placed on the severed ends 29 and 30 of the plastic core strips to completely seal and make the structure air tight. In this connection it will be noted that the normal shape of the sealing core is such that the outwardly protruding leg of the L-shaped core normally flares outwardly as shown in broken lines in Fig. 3 of the drawings and generally indicated by the reference character 32. When the installed panel is pressed into position, the flared ends of the core are compressed and the outer end of the core is slightly forced outwardly to form a curved crown as shown at 33. This arrangement positively seals and insures an air tight fitting between the marginal edges of the interlocking panels. The composition of the core also provides a yielding or flexible connection between the panels to allow for contraction and expansion as well as an efficient insulation.

Summarizing the advantages of my improved interlocking and sealing porcelain enamel panel, 75

it will be readily understood that I have provided a construction and an arrangement which will more efficiently maintain a permanent exterior or interior wall structure and one which will require no more attention or repair than an occasional washing to remove the dirt from the surface thereof. The simplicity of installation will reduce to a minimum the cost and at the same time eliminate the necessity of repairs or redecoration.

While in the above specification I have described one embodiment which my invention may assume in practice, it will, of course, be understood that the same is capable of modification and that such modification may be made without departing from the spirit and scope of the invention as expressed in the appended claims.

What I claim as my invention and desire to secure by Letters Patent is:

1. Architectural interfitting panels comprising substantially flat polylateral members, outwardly projecting flat flanges formed on certain of the marginal edges of said panels, outwardly projecting U-shaped flanges formed on the other marginal edges of said panels, said flat flanges projecting into the recesses formed by the U-shaped flanges, and preformed resilient means between the marginal edges of the adjacent panels embracing said flat flanges and yieldingly contacting said U-shaped flanges.

2. Architectural interfitting panels comprising substantially flat polylateral members, outwardly projecting flat flanges formed on certain of the marginal edges of said panels, outwardly projecting substantially U-shaped flanges formed on certain other marginal edges of said panels, said flat flanges extending into the central portions of the recesses formed by said U-shaped flanges, and preformed resilient means positioned between the marginal edges of the adjacent panels embracing said flat flanges and resiliently contacting said U-shaped flanges.

3. An architectural panel construction comprising a plurality of substantially flat polylateral panels, outwardly projecting flat flanges formed on certain of the marginal edges of and offset from the flat surface of said panels, there being outwardly projecting recesses formed on other marginal edges of said panels, said flat flanges 45 extending into the recesses of the next adjacent panels, and preformed resilient cores seated in said recesses and extending between the marginal edges of said panels, there being longitudinal slits in said cores for the reception of the flanges 50 of the adjacent panels.

4. An architectural panel construction comprising a plurality of substantially flat steel members having their marginal portions bent at right angles to the flat portions thereof, certain marginal portions terminating in flat flanges projecting beyond the marginal edges of said members, certain other marginal portions bent inwardly and thence outwardly, terminating in outwardly projecting flanges, said last named marginal portions forming relatively large recesses 60 therein for the reception of the thin flanges of the next adjacent members, and preformed resilient sealing cores snugly seated in said recesses and extending between the marginal edges of the adjacent panels and having flared-out portions 65 contacting with the marginal edges of said adjacent members, said cores having longitudinal slits on one side thereof for the reception of said flat flanges.

5. An architectural interlocking panel con-

struction comprising a plurality of main substantially flat steel members, certain marginal portions of said members bent and offset to form marginal flat flanges in the same plane parallel to the flat portions of said members, certain other marginal portions bent to form relatively large outwardly projecting substantially U-shaped recesses therein, said flat flanges extending into said U-shaped recesses, and pre-formed resilient sealing cores of a cross section complementary to said recesses, snugly fitting the spaces between said flat flanges and the walls of said U-shaped recesses and the spaces between the marginal edges of the adjacent panels.

6. Architectural interfitting panels comprising substantially flat polylateral members, outwardly projecting flat flanges formed on certain of the marginal edges of said panels, outwardly projecting substantially U-shaped flanges formed on the other marginal edges of said panels, said flat flanges projecting into the recesses formed by the U-shaped flanges, and preformed resilient means

between the marginal edges of the adjacent panels embracing said flat flanges and yieldingly contacting said U-shaped flanges, said resilient means having oppositely disposed flared out portions contacting the marginal edges of the adjacent panels.

CARL G. STRANLUND.
